Primary Examiner — Ruth McInroy(74) *Attorney, Agent, or Firm* — Banner & Witcoff, Ltd.**CLAIM**

The ornamental design for a handle for a vacuum cleaner, as shown and described.

DESCRIPTION

FIG. 1 is a front perspective view of a handle for a vacuum cleaner handle showing my new design;

FIG. 2 is a left side view thereof;

FIG. 3 is a right side view thereof;

FIG. 4 is a top plan view thereof;

FIG. 5 is a rear view thereof;

FIG. 6 is a bottom view thereof; and,

FIG. 7 is a front view thereof.

The broken lines shown in the figures represent portions of the vacuum cleaner handle that form no part of the claimed design.
